UNITED STATES PATENT OFFICE.

RICHARD JACOB AND EMIL SPECK, OF PASSAIC, NEW JERSEY.

DESIGN FOR WOVEN AND PRINTED RIBBON.

47,137.

Specification for Design.

Patented Mar. 23, 1915.

Application filed December 23, 1914. Serial No. 878,819. Term of patent 3½ years.

To all whom it may concern:

Be it known that we, RICHARD JACOB, a citizen of the United States, and a resident of Passaic, in the county of Passaic and State of New Jersey, and EMIL SPECK, a citizen of the Republic of Switzerland, and a resident of Passaic, in the county of Passaic and State of New Jersey, have invented a new, original, and ornamental Design for Woven and Printed Ribbon, of which the following is a specification, reference being had to the accompanying drawing forming part thereof.

The figure is a plan view of a section of ribbon showing our new design.

The flowers represent or are the characteristic ones of the States of the United States of America.

We claim:

The ornamental design for woven and printed ribbon, as shown and described.

RICHARD JACOB.
EMIL SPECK.
